(57) **CLAIM**

The ornamental design for a data storage device as shown and described.

DESCRIPTION

FIG. 1 is a front, first side, and top isometric view of a data storage device embodying the new design;

FIG. 2 is a front view thereof;

FIG. 3 is a rear view thereof;

FIG. 4 is a first side view thereof;

FIG. 5 is a second side view thereof;

FIG. 6 is a top view thereof;

FIG. 7 is a bottom view thereof;

FIG. 8 is a first cross-section view thereof along lines 8-8 in FIG. 6; and,

FIG. 9 is a second cross-section view thereof along lines 9-9 in FIG. 6.

The broken lines in the drawings depict portions of the data storage device that form no part of the claimed design. The shade lines indicate the character and contour of the surfaces represented, not to be confused with surface ornamentation.
